No. 37,326.

Patented February 7, 1905.

UNITED STATES PATENT OFFICE.

JOHN F. F. BJURMAN, OF PROVIDENCE, RHODE ISLAND.

DESIGN FOR A TOY BANK OR SIMILAR ARTICLE.

SPECIFICATION forming part of Design No. 37,326, dated February 7, 1905.

Application filed December 29, 1904. Serial No. 238,857. Term of patent 7 years.

To all whom it may concern:

Be it known that I, JOHN F. F. BJURMAN, a citizen of the United States, residing at Providence, in the county of Providence and State 5 of Rhode Island, have invented a new, original, and ornamental Design for a Toy Bank or Similar Article, of which the following is a specification, reference being had to the accompanying drawing, forming part thereof.

10 The figure is a perspective view of a toy bank or similar article, showing my new design.

What I claim as new, and desire to secure by Letters Patent, is—

The ornamental design for a toy bank or 15 similar article, as shown.

JOHN F. F. BJURMAN.

In presence of—

THOMAS F. FARRELL,
HENRY A. PALMER.
